Specification for Design.

Patented July 13, 1920.

Application filed April 17, 1920. Serial No. 374,754. Term of patent 14 years.

To all whom it may concern:

Be it known that I, HARRY J. ROEBUCK, a citizen of the United States of America, and a resident of Troy, New York, (whose post-office address is #224 Eighth street, Troy, New York,) have invented a new, original, and ornamental Design for a Snap-Hook, of which the following is a specification, reference being had to the annexed drawing, forming part thereof.

In said drawing:—

Fig. 2 is a plan view of the same.

What is claimed is:—

The ornamental design for a snap hook, as shown.

In testimony whereof I have signed this specification.

HARRY J. ROEBUCK.
